United States Patent

Des. 236,928
Patented Sept. 30, 1975

236,928

SHELF UNIT

Hans Paul Ludwig Geisler, Norderstedt, Germany
(Sechslingspforte 2, 2000 Hamburg 76, Germany)

Filed Jan. 18, 1974, Ser. No. 434,719

Term of patent 14 years

Int. Cl. D6—04

U.S. Cl. D6—186

FIG. 1 is a perspective view of a shelf unit showing my new design;

FIG. 2 is a top plan view thereof;

FIG. 3 is a modified form of the shelf unit shown in FIG. 1; and

FIG. 4 is a top plan view thereof.

I claim:

The ornamental design for a shelf unit, as shown.
